CLAIM

We claim the ornamental design for a pair of motorcycle spoilers, as shown and described.

DESCRIPTION

FIG. 1 is a left side elevational view of a left spoiler showing our new design;

FIG. 2 is a right side elevational view of a right spoiler according to the present design;

FIG. 3 is a top plan view of the right spoiler;

FIG. 4 is a top plan view of the left spoiler;

FIG. 5 is right (inner) side elevational view of the left spoiler;

FIG. 6 is a left (inner) side elevational view of the right spoiler;

FIG. 7 is a perspective view, from below, of the left spoiler;

FIG. 8 is a perspective view, from below, of the right spoiler;

FIG. 9 is a view, from above and behind, of the left spoiler;

FIG. 10 is a view, from above and behind, of the right spoiler;

FIG. 11 is a view, from above, of the left spoiler;

FIG. 12 is a view, from above, of the right spoiler; and,

FIG. 13 is a front perspective view of the left spoiler; a front perspective view of the right spoiler is a mirror image of the front perspective view of the left spoiler.

1 Claim, 13 Drawing Sheets
